SAFETY LATCH

Charles D. Best, Fresno, Calif.

Application November 28, 1950, Serial No. 197,898

5 Claims. (Cl. 292—203)

1

The present invention relates to latches and more particularly to a safety latch for window screens, windows, doors, lids, shutters and the like. The latch has particular utility in association with a movable closure member, such as a window, to retain an auxiliary closure member, such as a window screen, in closed position and is conveniently described in connection with such use.

Window screens are conventionally latched in fitted relation to their respective frames by means of the well known hook and eye devices. It is the usual practice screw-threadedly to mount the eyes in window frames adjacent to window screens received thereby and swivelly to connect hooks to the screens for releaseable engagement with the eyes. The structure is economical and usually retains the screens in closed position against accidental displacement thereof but is subject to certain difficulties which the present invention seeks to overcome.

It is well known that conventional hook and eye latches offer no protection against illegal entry in that the latches are readily disengaged from their respective eyes merely by extending a slender wire or the like through the screen and effecting the disengagement. Further, shrinking and swelling of wooden window frames and screens fitted thereto frequently causes a loosening of hook and eye engagement so that slight jostling of the screen incident to a wind or the like causes the hooks to fall from eye engagement. Thus, the conventional hook and eye structures are not always dependable in maintaining latched association against even inadvertent or accidental disengagement.

An object of the present invention is therefore to provide an improved latch for window screens, windows, doors, lids, shutters, and the like.

Another object is to provide a latch of the character described that is characterized by improved safety and resistance to accidental release as well as deliberate release from externally of a closure member held thereby.

Another object is to provide a latch having particular utility in maintaining a movable closure member such as a window screen in closed position and which is adapted to be locked in latching position by overlaid engagement with an associated closure member, such as a window sash.

Another object is to provide a latch for window screens that is substantially impossible to release from externally of a screen held thereby.

2

Other objects and advantages are to provide improved elements, configurations, and arrangements thereof in a device of the character and for the purposes set forth that is economical to produce, durable, and fully effective in performing its intended function.

Further objects and advantages will become apparent in the subsequent description in the specification.

In the drawing:

Fig. 1 is a fragmentary plan view of a window sill and fragmentary horizontal section of a window screen showing in plan view a latch embodying the principles of the present invention, the illustrated members being shown in the relative position assumed at the initiation of a latching operation before the screen is fully closed.

Fig. 2 is similar to Fig. 1 except that the members shown therein are illustrated at the completion of the latching operation.

Fig. 3 is a vertical section through a window frame, window sash, and window screen, showing the latch of the present invention in side elevation in its relation to the associated members shown in Fig. 2.

Fig. 4 is a perspective view of the latch of the present invention.

Fig. 5 is a fragmentary section of a window frame and window sash showing in fragmentary section a latch of the present invention in a modified mounting position as compared with the mounting shown in Fig. 3.

Referring in greater detail to the drawing:

A window sill 10 is shown as comprising a portion of a window frame 11. The frame mounts a window sash 12 for vertical sildable movement and fitted engagement against the sill 10. A window screen 14 is mounted in any suitable manner, not shown, for fitted engagement into the frame 11 in spaced relation to the sash 12.

“Window screen” as employed herein is intended to denote a member having a suitable frame and an opening therein covered by wire screen mesh, as is usually intended in the trade. Although the screen, frame and sash are shown as formed of wood, it will be understood that the latch of the present invention is not limited to employment with such material.

The latch of the present invention is indicated generally at 20 and includes an elongated flat plate 21 of metal, plastic or other suitable material having an upturned flange 22 extended generally longitudinally of the plate from an end thereof. A blade 23 is upwardly extended from the opposite end of the plate 21 and is

generally transversely disposed to the plate. The blade may provide a sharpened upwardly extended edge, if desired.

Intermediate the flange and the blade, a locking slot 25 is formed substantially transversely in the plate. The slot provides an enlarged opening 26 adapted to receive a locking pin, subsequently to be described, an elongated central portion 27 arcuately extended from the opening 26 transversely of the plate and somewhat endwardly toward the end of the plate providing the flange 22. The slot 25 has a locking portion 28 continuous with the elongated portion extended from said elongated portion transversely of the plate and arcuately away from the end of the plate provided with the flange. It is significant that the locking portion 28 is aligned with the flange 22, as shown.

A connection 30 is swivelly mounted in the flange 22 near the adjacent end of the plate and is adapted for screw-threaded mounting in the screen 14 or other closure member to be latched in closed position.

A locking pin 33, such as a headed screw, is mounted in the sill 10 in spaced relation to the swivel connection 30 and either intermediate the screen 14 and sash 12, as shown in Fig. 3, or beneath the sash 12, as shown in Fig. 5. As evident in Figs. 1 and 2, the locking pin is positioned for convenient reception by the opening 26 as the screen 14 is moved toward fitted position in the frame 11 and so that when the plate 21 is pivoted so as to receive the pin in the locking portion 28 of the slot the plate is tensioned by the pin and the connection 30 mounted in the screen.

Operation

The operation of the latch of the present invention is believed to be clearly apparent and briefly summarized at this point. The latch is mounted for use by securing the swivel connection 30 in a closure member such as the screen 14 in a position so that the plate 21 may rest on the sill 10 and the blade 23 extend under the window sash 12 or other associated closure member. The pin is positioned as described either intermediate the screen and sash or beneath the sash, as convenience suggests. The swivel connection 30 and pin are properly spaced for convenience of reception of the pin in the opening 26 as the screen 14 is moved toward fitted position in the frame 11. The screen is conveniently drawn tightly into fitted position if the pin 33 and swivel connection 30 are properly positioned, by pivoting the plate 21 to move the pin along the slot 25 and bring the plate to rest with the pin in the locking portion 28 aligned with the flange 22. In such position the plate is tensioned between the screen and pin.

The swivel connection 30 and pin 33 are so positioned that when the latch plate is pivoted into latching position, as just described, the blade 23 is upwardly extended below the sash 12. When a wooden sash is employed, it is forcibly seated against the sill 10 and the blade 23 cuts its own slot upwardly into the sash as indicated at 35. When sashes other than wooden sashes are employed, a slot is cut in the bottom of the sash to receive the blade 23. Similarly, the sash is formed to receive the head of the pin 33 if said pin is mounted below the sash.

When a screen is latched in the manner described it will be noted that a line radially of the swivel connection 30 passed through the pin 33 will pass longitudinally through the flange 22.

The tension of the plate and flange facilitates maintenance of the pin 33 and the locking portion 28 of the slot 25. When the sash 25 is seated in the sill 10 over the blade 23, sash and blade 5 engagement effectively precludes pivotal movement of the plate 21 to disengage the pin 33. Further, the engagement of the blade 23 in the slot 35 aids in resisting outward movement of the screen 14 and effectively obviates forcible pulling of the screen from latched position without physical destruction of portions of the screen, sill, and/or sash.

It is impossible to release the latch when the sash 12 is in seated position on the blade 23 by 15 the extension of a lever through the screen and attempting to pry the plate laterally by engagement of such a lever with the pin. Primarily, such prying is resisted by blade and sash engagement. Secondly, the flange in the attitude described, makes it extremely difficult to engage the pin 33 with a lever thrust through the screen for prying purposes. It will be noted that the end of the flange 22 adjacent to the slot 25 is downwardly slanted. This effectively precludes 25 prying against the flange for any lever employed for such purpose slips up the slanted end as soon as any appreciable force is exerted thereon.

The latch of the present invention provides improved safety characteristics as compared 30 with conventional latches for the purpose and is fully effective in precluding inadvertent or accidental unlatching thereof as well as deliberate efforts to unlatch the same from exteriorly of the screen. The latch is economical to produce, convenient and easy to install, even by a novice, and of durable form when fabricated from metal, plastic, fabric, or other suitable material.

Although the invention has been herein shown and described in what is conceived to be the 40 most practical and preferred method and embodiment, it is recognized that departures may be made therefrom within the scope of the invention, which is not to be limited to the details disclosed herein but is to be accorded the full scope of the claims so as to embrace any and all equivalent devices and apparatus.

Having described my invention what I claim as new and desire to secure by Letters Patent is:

1. A latch comprising a plate, and means 50 mounted on the plate adapted swivelly to mount the plate on a closure member, said plate having a blade extended in substantially right angular relation therefrom in spaced relation to the mounting means and a locking pin receiving slot formed in the plate intermediate the mounting means and blade.

2. A latch adapted for use with a window frame having a window sill, a window sash mounted in the frame for slidable movement therein and seated engagement with the sill, and a window screen movable to and from fitted engagement in the frame; comprising a flat plate rested on the sill having a locking pin receiving slot formed therein, means swivelly mounted on an end of the plate connected to the screen, and a locking pin mounted on the sill releasably engaged in the locking pin receiving slot of the plate to lock the plate tensioned between said pin and the screen, said plate being extended between the window sash and the sill and having a blade in right angular relation thereto extended releasably into the sash.

3. A latch adapted for use with a window frame having a window sill, a window sash mounted in the frame for slidable movement

therein and seated engagement with the sill, and a window screen movable to and from fitted engagement in the frame, comprising an elongated flat plate rested on the sill having an upturned flange at an end thereof extended longitudinally of the plate and an upturned blade at the opposite end of the plate extended transversely of the plate, a swivel connection mounted on the flange adjacent to its respective end of the plate and connected to the screen, the plate having a locking slot formed generally transversely therein intermediate the swivel connection and the blade, and a locking pin mounted in the sill in a position to be received by the slot in the plate with the plate tensioned between the screen and said pin when the screen is in fitted position in the frame and with the swivel connection positioning the blade between the sill and the window sash for extension of the blade into the sash when the sash is seated on the sill.

4. A latch comprising an elongated plate having an upturned flange at an end thereof extended longitudinally of the plate and an upturned blade at the opposite end of the plate extended transversely of the plate, and a swivel connection mounted on the flange adjacent to the end of the plate adapted for connection to a closure member, the plate having a kidney slot formed generally transversely therein between the flange and blade adapted to receive a locking pin, said slot having an enlarged opening, an elongated curved portion continuous with the opening extended transversely of the plate and radially inwardly relative to the swivel connection, and a locking portion continuous with the elongated portion extended transversely of the plate and radially outwardly relative to the swivel connection and terminated in substantial alignment with the flange.

5. In combination with a window frame having a window sill, a window sash mounted in the frame for slideable elevational movement therein and seated engagement with the sill, and a window screen movable to and from fitted relation to the frame; a latch comprising an elongated flat plate rested on the sill having an upturned flange at one end thereof extended longitudinally of the plate and an upturned blade at the opposite end of the plate extended transversely of the plate, a screw eye mounted in the screen and swivelly connected to the flange of the plate whereby the plate may be moved pivotally over the sill, and a locking pin mounted in the sill intermediate the screw eye and the window sash, the plate being formed with a generally transverse slot having an enlarged end adapted to receive the pin when the screen is outwardly displaced from fitted position and an opposite end in substantial alignment with the flange spaced transversely of the plate from the enlarged end and radially inwardly of the swivel connection of the screw eye thereto whereby the plate is tensioned in latching position between the screw eye and the pin when the screen is in fitted position and the pin received in said opposite end of the slot, the plate being of such length that when in latching position the blade is extended upwardly into the window sash when the sash is seated on the sill.
